(57) CLAIM

The ornamental design for a beverage can opener, as shown and described.

DESCRIPTION

FIG. 1 is a front elevational view of a beverage can opener showing our new design;

FIG. 2 is a rear elevational view thereof;

FIG. 3 is a side view, taken from the left side of FIG. 1;

FIG. 4 is a side view, taken from the right side of FIG. 1;

FIG. 5 is a top plan view thereof, the bottom plan view being a mirror image thereof; and,

FIG. 6 is a perspective view thereof.

The broken line showing a key ring in the figures are for illustrative purposes only and form no part of the claimed design.
